UNITED STATES PATENT OFFICE.

CHARLES J. LIETZ, OF MIDDLETOWN, NEW YORK, ASSIGNOR TO IDEAL WRAPPING MACHINE COMPANY, A CORPORATION OF NEW YORK.

WRAPPING-MACHINE.

1,359,181.

Specification of Letters Patent. Patented Nov. 16, 1920.

Application filed March 17, 1917. Serial No. 155,420.

To all whom it may concern:

Be it known that I, CHARLES J. LIETZ, a citizen of the United States, and a resident of the city of Middletown, in the county of Orange and State of New York, have invented certain new and useful Improvements in Wrapping-Machines; and I do hereby declare that the following is a full, clear, and exact description of the same, reference being had to the accompanying drawings, and to the numerals of reference marked thereon, which form a part of this specification.

This invention relates to an improved form of wrapping machine particularly adapted for wrapping caramels, although, of course, adapted to wrap other similar articles, and by slight modification, capable of wrapping other different objects. The machine embodying my invention is designed to handle fresh caramels in their yieldable state without injury and as well to take care of caramels which vary in size, whereby an individual wrapper is applied around each caramel. The machine is designed for use with a power drive and with the caramel feeding table and discharge chute for the wrapped caramels conveniently arranged for access by a single operator. All parts of the machine are easily accessible for ready adjustment or repair when necessary.

The machine embodying the principles of my invention differs from other types of wrapping machines in many particulars, notable among which may be mentioned the fact that the article receives the wrapper applied upon and folded therearound, while continuously moved along on a carrying member, with various movable and stationary devices to perform the different folding operations so that the article, when ejected from the carrying member, is completely wrapped.

It is an object therefore of this invention to provide a wrapping machine adapted to apply and fold a wrapper around an article during a continuous progress of the article, and furthermore, folding the wrapper upon the article in a new manner whereby the folds of the wrapper are interlocked with one another upon the article to obviate subsequent accidental unfolding of the wrapper from the article.

It is also an object of this invention to

construct a wrapping machine employing a wrapping wheel which is brought to rest by a stop motion mechanism to receive an article together with a wrapper for the article deposited in a pocket in the wheel, and thereafter moving continuously, carrying the article and the wrapper through the field of operation of folding devices which serve to completely fold the wrapper around the article prior to ejection of the article from the wrapping wheel.

It is also an object of this invention to construct a wrapping machine wherein an individual wrapper for each article is cut from a continuous reel of wrapping material and properly disposed to receive the article thrust therewith into a wrapping wheel, which then serves by its movement, to carry the article into the field of operation of folding devices which serve to fold the wrapper around the article, certain of said devices over-traveling the wheel, and others mounted in stationary position to perform the various folding operations upon the wrapper.

It is a further important object of this invention to construct a wrapping machine wherein an intermittent drive is imparted to certain of the mechanisms through an improved device for the purpose to permit a continuous application of power to the machine without shock from entrainment of the mechanisms as they are intermittently operated, thus providing a smooth running machine.

It is also an object of this invention to construct a wrapping machine provided with improved wrapping mechanisms and improved feeding and discharging devices, as well as an adjustable means for feeding wrappers of any predetermined size to the feeding devices for application on an article.

Other and further important objects of this invention will be evident from the disclosure in the specification and drawings.

The invention (in a preferred form) is illustrated in the drawings and hereinafter more fully described.

On the drawings:

Fig. 46 illustrates first application of the wrapper upon the caramel.

Fig. 47 illustrates the first folding operation.

Fig. 48 illustrates the folds completed on the top side, and the first end fold on the caramel.

Fig. 49 illustrates the second end fold on the caramel.

Fig. 50 illustrates the third end fold on the caramel.

Fig. 51 illustrates the final side fold of the wrapper upon the caramel.

Fig. 52 is a bottom plan view taken on line 52—52 of Fig. 3.

As shown on the drawings:

Referring to Fig. 1, the caramel feed table is denoted as a whole by the reference nu-

meral 1, and is provided with a raised border or inclosing wall 2, on three sides thereof. Mounted upon the table 1, adjacent the other edge thereof is a long plate 3, having a downwardly beveled edge, and beneath said plate is a slidably beveled edge plate 4.

125 130

Said plate 3, is provided with guide slots 5, at each end thereof, engaged by guide pins 6, secured in the plate 4, and with clamping bolts 7, engaging through said slots to hold 5 the plate in various adjusted positions. Disposed below the beveled edge of said plate 4, is a grooved guide member 8, over which the upper run of a feed belt 9 is adapted to travel, whereby the caramels may be fed onto 10 said belt from the table and carried therefrom to wrapping position. Said belt is provided with a series of pockets, each adapted to receive a caramel, and said pockets are formed, as clearly shown in Fig. 25, by looping 15 the belt fabric outwardly, as denoted by the reference numeral 10, through a transversely disposed rectangular shaped tube or eye 11, with a steel insert 12, engaged into the interior of the loop and having a central 20 downwardly extending projection or tooth 13. The downwardly projecting tooth members 13, of the carrier feed belt 9, track in the groove of the guide member 8. A bracket 14, is secured on the under side at one end 25 of the feed table 1, and slidably mounted thereon against spring stress is an idler tension pulley or sheave 15, which is peripherally grooved and around which the belt 9, is trained, with the toothed members 13, 30 fitting into the groove of the pulley.

Pivottally mounted at the forward end of the feed table 1, and extending into a slot in the beveled edge of the plate 4, is a stripper bar 16; one edge of which is chamfered 35 off, and said stripper bar extends over the pockets in the belt to prevent more than one caramel being carried in each thereof and serving to tilt an improperly carried caramel into proper position. A long bar 17, having 40 attaching rods 18, secured at each end thereof, is mounted adjacent the outer edge of the belt 9, and the rods thereof are adjustably connected into apertured bosses 19, forming a part of the frame structure of the 45 feed table, so as to permit adjustment transversely of the bar toward and away from said belt.

The wrapping machine to which the feed table and feed mechanism is connected embraces a base frame casting 20, and supported upon the upper portion of said base 20, is a block casting 21. Secured on the front end of said casting 21, is a frame plate 22, having a lateral curved arm extension 23. 50 Mounted on the upper portion at the forward end of the frame casting 21, is an upright frame plate member 24, and mounted upon the upper rear portion of said frame casting 21, is a bearing block 25, affording 55 two alined shaft bearings 26 and 27, with a shaft 28, journaled therein. Secured upon the outer end of said shaft 28 is a hand wheel 29, by which movement may be imparted to the shaft for the purpose of ad-

justing, setting, or timing any of the mechanisms driven therefrom when necessary. 65

Also secured upon said shaft 28, is a worm gear 30, which meshes with another worm gear 31, at right angles thereto, and mounted upon a shaft 32, which is journaled in a bearing extension 33, formed integral with and beneath the bearing member 26. Journaled in a bearing extension 34, at one side of the bearing member 25, is a shaft 35, and secured on the inner end thereof is a Geneva gear 36, shown in detail in Fig. 9. Mounted on the outer end of the shaft 32, is an eccentric disk 37, provided with a pin 38, which is adapted to sweep into recesses in said Geneva gear as the pin is rotated around with 80 said disk to advance the Geneva gear and its shaft 35, intermittently. The outer end of the shaft 32, on which said disk is mounted, is cut away and curved, as clearly shown in Fig. 9, the curved portion registering with 85 the outer peripheral surface of the Geneva gear between the recesses therein as the Geneva gear is advanced a certain amount for each rotation of the disk 37.

Secured upon the outer end of said shaft 90 35 is a sprocket wheel 39, and trained thereabout is a chain 40. A bearing bracket 41, is adjustably mounted on the rear surface of the frame plate or arm 23, and journaled therein is a notched wheel 42, having 95 notches 43, therein, as shown clearly in Fig. 23, and around which the feed belt 9, is trained. Rigidly but adjustably connected to said belt wheel 42, is a sprocket wheel 44, connected by screws 45, extending through 100 slots in said sprocket wheel into the belt wheel, and said driving chain 40, is trained around said sprocket wheel whereby the belt wheel is driven from the driving sprocket 39. The adjustment between the 105 sprocket wheel 44, and belt wheel 42, admits timing of the movement of the belt for certain positions of other mechanisms of the wrapping machine hereinafter described, for proper operation thereof. 110

Journaled upon said shaft 28, is a large worm gear 46, and journaled therebeneath in bearings provided in the base portion of the member 25, is a worm shaft 47, meshing with said worm gear, and on its outer 115 end provided with a driving pulley 48, adapted to be driven by any suitable source of power. Feathered upon said shaft 28, adjacent to the worm gear 46, is a ratchet faced slidable clutch 49, adapted to be 120 moved into engagement with ratchet teeth formed upon the hub of the worm gear 46, to lock the worm gear to the shaft 28, whereby the shaft 28, may be driven thereby. Pivoted upon an upright pintle 50, secured on the bearing member 25, is a 125 forked clutch lever 51, the forked end of which engages the groove in the slidable

clutch member 49, in order that by actuation of said lever, the clutch may be thrown in or out to lock or unlock the driving gear 46, to or from the shaft 28. A vertically mounted spring impelled detent 52, is mounted at one side on the bearing member 25, beneath the lever 51, and said lever is provided with a downwardly extending projection 53, beveled off on each side at its lower end against which said detent bears, to hold said lever either in one or another position for engaged or disengaged position of the clutch 49.

Keyed upon said shaft 28, adjacent to the bearing 27, is a cam wheel 54, having one cam groove 55, in one surface thereof and another cam groove 56, in the opposite surface thereof. Secured upon the shaft 28, adjacent to said cam wheel 54, is a bevel gear 57, slightly beyond which said shaft 28, terminates. Journaled in a bearing extension 58, secured upon the front surface of the frame plate 24, is a shaft 59, which extends inwardly in alinement with the shaft 28, terminating close to the end of the shaft 28, and journaled on the adjacent inner ends of said respective shafts 28 and 59, is a spider 60, having an arm extension 61, and provided with stud shafts 62, diametrically disposed, each having journaled thereon a bevel pinion 63. Another bevel gear 64, is secured upon the shaft 59, in mesh with the respective bevel pinions 63. The gears 57, 63 and 64, form a differential or reverse gear drive construction whereby the shaft 59, is driven in reverse direction to, and by the shaft 28, and may be brought to rest and accelerated by adjustment of the spider carrying the pinions 63, in a manner herein-after described.

Secured in upright position upon one side of the frame casting 21, is a bearing standard 65, in which is journaled a shaft 66, which also extends through a bearing formed in the frame plate 24. Connected on the end of said shaft 66, beyond the frame plate 24, is a depending crank 67, for a purpose hereinafter pointed out. Secured upon the other end of the shaft 66, beyond the upright bearing 65, is a crank 68, provided at its end with a roller 69, engaged in the cam groove 55, of the cam wheel 54. Journaled on said shaft 66, on the other side of said bearing upright 65, is a long crank 70, provided near its middle portion with a roller 71, engaged in the cam groove 56, of the cam wheel 54. Pivottally connected to the outer end of the crank 70, is a link 72, which is also connected at its other end to the crank 61, whereby movement of the crank 70, due to travel of the roller 71, in the cam groove 56, imparts an oscillatory movement at certain intervals to the spider 60, carrying the bevel pinions 63. Also secured upon the shaft 59, adjacent the

bevel gear 64, is another cam wheel 73, having a cam groove 74, in one surface thereof.

Secured rigidly upon the outer end of the bearing 58, of the frame plate 24, is a stationary cam member 75, having a cam groove 76, in the outer surface thereof. Secured upon the outer end of the shaft 59, which extends through and beyond said bearing member 58, and cam element 75, is the carrying or wrapping wheel, consisting of a circular ring 77, with a diametrical cross-piece 78, integral therewith, and on which is formed a hub 79. As shown clearly in detail in Fig. 6, the hub 79, is held attached to a disk portion 80, formed on the end of the shaft 59, by dowel pins 81, and screws 82. The diametrical cross-piece 78, is slotted out for almost its entire length, and slidably in said slot is a block 83, having secured on each side thereof and overlapping the edges of the crosspiece, plates 84, held attached by a pin 85, and screws 86. Adjustably attached upon the outer ends of said plates 84, are end folder plates 87, held attached by means of screws 88, engaged through slots in said plates to clamp the same in adjusted position. A carrying pocket for a caramel is formed in the wrapping wheel in that end of the cross-piece 78, at which the end folder plates 87, are disposed, as shown in detail in Fig. 37. The side walls of said pocket are formed by resilient plates 89, engaged at their lower ends in slots provided therefor, and at their upper ends bent outwardly and then inwardly to engage in recesses 90, provided therefor in the periphery of the carrying wheel, so that when the caramel is thrust into said pocket, said plates are sprung and serve to retain the caramel therein. Slidably mounted through a passage provided through one end of the cross-piece 78, as shown clearly in Figs. 5 and 37, is a cylindrical plunger 91, having a head 92, which forms the bottom of the caramel pocket in the wheel, and at its other end is provided with a head 93, adapted for contact with the upper end of the slide block 83. A set screw is engaged through one side of the cross-piece 78, to engage the plunger and prevent rotation thereof in its passage.

Secured transversely through one end of the block 83, is a pin 94, held attached therein by a screw 95, and washer 96, and secured in the end of said pin is a small stud shaft 97, on which is journaled a roller 98, which tracks in the cam groove 76, of the stationary cam element 75. Thus, as the wrapping wheel rotates, the roller 98, traveling in the cam groove, will cause the block 83, to slide diametrically of the wrapping wheel and thus actuate the end folder plates 87, as well as the ejecting plunger head 92.

Resting upon the upper periphery of the 130

wrapping wheel 77, is a curved or arc-shaped shoe 99, which, for its major portion, is narrower than the surface of the wrapping wheel, but at its forward end is 5 provided with a wide outwardly curved head 100, extending beyond the sides of the wrapping wheel. The rear or trailing end of said shoe 99, is rounded on its outer surface and tapered inwardly to a width less 10 than the surface of the wrapping wheel, and is denoted by the reference numeral 101, as shown clearly in Fig. 38. Near its forward end, said shoe 99, is pivotally connected on a rod 102, which is rigidly but 15 adjustably mounted in a sleeve 103, which is in turn pivoted upon a stud 104, secured in a boss extension on the frame plate 24. Said shoe 99, rests upon the periphery of the wrapping wheel and holds its position 20 by gravity.

Another curved or arc-shaped shoe 105, is spring thrust against the left peripheral face of the wrapping wheel, and the forward end of said shoe 105, flares outwardly 25 and is of V-shape, as shown clearly in detail in Fig. 38, the ends of the V-portion, denoted by the reference numerals 106, spaced apart a distance greater than the width of the peripheral face of the wrapping wheel. 30 The under surface of said V-points 106, are tapered or rounded, as clearly shown in detail in Fig. 39, thus fitting around, though spaced from the tapered portion 101 of the shoe 99. The bevel of the V-points 106 35 is so designed that the action of one is in advance of the other so that one end fold is bent over slightly in advance of the other as is common in the art so as to prevent the end folds coming together in a jam. Said shoe 105, is pivotally connected on the lower 40 end of a crank 107, which is connected on a pintle 108, secured in lug extensions 109, of a bracket 110, secured upon the front frame plate 24. A coiled spring 111, is secured around the pintle 108, and to the 45 crank or lever 107, and acts normally to thrust said lever inwardly to hold the shoe 105, closely against the periphery of the wrapping wheel. A wedge shaped block 50 111^a is attached to the lower end of the shoe 105, and pivotally connected thereon is a flat resilient metal guide bar 112, which fits over a discharge chute hereinafter described, and beneath which the caramels ejected 55 from the machine are moved.

Also pivotally mounted upon the bracket 110, parallel to the frame plate 24, are a pair of pintles 113, upon which are pivoted end folder plate arms 114, connected by a 60 spring 115, so as to be normally drawn toward one another, as shown clearly in detail view in Fig. 34, and each arm at its lower end is provided with a folder plate 116, the forward edge of each of which curves 65 smoothly outwardly into position slightly

in advance of the point at which the shoe 105, overlaps the shoe 99, on the wrapping wheel. Adjustable upon each of the folder plates 116, are light stamped metal breaker plates 117, attached by screws 118, and the 70 forward edges of said plates are curved outwardly, and are disposed in advance of the forward edges of the folder plates 116, so as to strike the outer portions of the wrapper as the caramel is carried around on the 75 wrapping wheel, prior to the time at which the folder plates 116, contact the wrapper. Thus said breaker plates initiate the bend in the wrapping material which is completed as end folds by the folder plates 116, preventing possible injury to the wrapper. 80

Formed upon the upper portion at one side of the frame plate 24, is a boss extension 119, through which is journaled a shaft 120, with a pair of folder arms 121, adjustably clamped or secured on the outer end thereof by means of set screws 122. Formed at the lower ends of the arms 121, are end folder heads 123, the inner surface of each of which for contact with the wrapper, is curved smoothly outwardly. The other end of said shaft 120, as shown in Fig. 12, has attached thereon a bell crank having arms 124 and 125, respectively. Connected to the arms 124, is a link 126, which is also connected to the end of a crank 127, pivoted upon a stud 128, secured in the rear surface of the frame plate 24. Said crank 127, is provided with a roller 128, which projects into the cam groove 74, of the cam wheel 73, 100 and by travel of the cam 73, receives a distinctive movement, which is transmitted to the bell crank 124—125, and shaft 120, by which the end folders 121—123, are operated. 105

Connected to the arm 125, of the bell crank, is a long link or lever 129, which is connected to a crank 130, secured upon a shaft 131, journaled through an extension provided on one side of the frame plate 24. 110 Attached upon the other end of the shaft 131, at the front of the frame plate 24, as clearly shown in Figs. 14 to 17, inclusive, is a wheel 132, secured adjustably on said shaft 131, by a set screw or other means. 115 Attached upon said wheel 132, is a bent arm 133, having a relatively wide curved surface folder head 134, formed on the end thereof adapted when the wheel 132, is oscillated, to strike the wrapper, as shown in 120 Fig. 14, to initiate the first fold thereon. The folder head 134, is operated co-incidentally with the end folders 121—123, the folder head 134, being swung inwardly as the folder heads 123, are swung outwardly 125 and vice versa, with respect to the wrapping wheel, due to the fact that the respective folders are both operated from the cam wheel 73.

The caramels are carried into the ma- 130

chine upon the feed belt 9, and as the feed belt stops for an instant due to the intermittent drive thereto, a caramel is thrust into the pocket in the wrapping wheel with 5 a sheet of wrapping material associated therewith for application around the caramel. For this purpose, attached upon the curved arm extension 23, of the frame plate 22, is a hollow casting 135, having a shelf 10 extension 136, at the forward end thereof, as shown in Fig. 19, and mounted upon said shelf extension is a forming box 137, which is provided with a passage 138, therethrough, the side walls of which are convergent, as clearly shown in Fig. 32. The top 15 wall of the forming box is formed by a plate 139, the under surface of which over the passage 138, is convergent inwardly, and said plate at its rear end is provided with downwardly extending arms 140, which, as clearly shown in Fig. 33, form a fork for a pivotal connection of said plate by means of a pintle 141, extending through the forward end of a rectangular frame or casting 20 142, secured upon the upper surface of the hollow casting 135. Mounted in a beveled slot in said plate 139, is a roller 143, of a diameter greater than the width of the slot so as to rest therein, and a resilient spring 25 144, is secured upon the upper surface of the plate 139, and bears upon said roller to confine the roller in said slot. Pivottally connected at the rear end of the plate 139, is a threaded rod 145, which extends 30 through a notched lug 146, formed upon a top plate 147, which is secured over the rectangular frame 142. A washer 148, is engaged on said rod 145, and bears against the notched lug 146, and threaded on said 35 40 rod near the other end thereof is a knurled head 149, with a compression spring 150 seated thereagainst and coiled about said rod and bearing on said washer 148, whereby said plate 139, is thrust downwardly by said 45 spring into close contact with the top surfaces of the side walls of the forming block 137.

Attached across the forward end of the plate 139, and spaced therefrom, as clearly 50 shown in Fig. 19, is a bar 151, affording a breaker strip and guide for the wrapping material introduced in front of the forming box. A similar breaker strip or bar 152, is attached across the front edge of the forming box 137, beneath the passage 138, and spaced from the forming box to receive the paper wrapper introduced theretwixen. The caramel feed belt 9, travels beneath the plate 139, in front of the passage of the 55 60 forming box, as shown by Figs. 1 and 4.

As shown in Fig. 19, a plunger 153, is slidable through the frame 142, and is provided with a head 154, at its forward end. Mounted on the under side of said plunger 55 is a rack 155, and meshing therewith is a

sector gear 157, secured upon a shaft 158, which is journaled transversely through the lower portion of the casting 135. Also secured upon said shaft, as shown in Fig. 21, 70 is a crank 159, to which a link 160, is connected, and said link is also connected to a block 161, formed or secured upon a slide bar 162, slidable longitudinally through the lower portion of the casting 135. A link or lever 163, is connected to the forward end 75 of the slide bar 162, and to the lower end of the crank or lever 67, shown in Fig. 8. Journaled on the inner surface of the frame plate 23, within the hollow casting 135, is a bell crank having one arm 164, provided 80 with a roller 165, which engages in a cam groove 166, in the block 161, and the other arm of which, denoted by the reference numeral 167, extends downwardly below the frame casting 135. Plates 168, are attached 85 on the under side of the frame casting 135, at the forward and rear ends thereof, upon which the slide bar 162, rests.

Attached upon the front surface of the frame plate 22-23, as clearly shown in 90 Figs. 4, 7 and 31, is a small casting 169, having one upwardly convex curved top portion with a curved housing extension 170, at one side thereof, and with a cover plate 171, attached across the front end of the 95 portion 169. Secured upon the top surface of the frame member 169, is an angle shaped bracket member 172, shown in Figs. 4 and 27, and secured thereto and projecting upwardly therefrom, and extending downwardly through a slot in the casting 169, is a paper guide tube 173. Attached upon the upper end of the paper tube 173, is a wide plate 174, with guide channels 175, adjustably secured thereon, adjustable for 100 different widths of paper strip. Within the casting 169, merely the flat side walls of the tube 173, extend downwardly therethrough, the end walls of the tube only extending into the casing slightly below the top wall thereof. The paper strip is fed upwardly from the guide members 173, between the breaker strips 151 and 152, and interposed in the gap between said guides and said breaker strips is a paper shearing mechanism. 110

This mechanism is supported upon the forward portion of the frame casting 21, and for this purpose, as shown in Figs. 7 and 43, a bracket 176, is secured upon said frame casting 21, and mounted in upright position 120 therein is a shaft or rod 177. Adjustably mounted upon the upper end of said shaft 177, for slidble adjustment with respect thereto, is a bracket 178, held from rotation thereon by a key 179, formed or secured on the shaft 177. An upright threaded shaft or bolt 180, is mounted in the upper end of the bracket 176, and has threaded engagement with the bracket 178, whereby rotation of said threaded rod will serve to elevate or 125 130

lower the bracket 178. Rigidly secured upon an extension of the bracket 178, is a horizontally disposed shearing blade 181, and disposed to co-act therewith in shearing the paper is a pivotal shearing blade 182, secured upon an upright shaft 183, journaled in said bracket 178. Attached upon the lower end of said shaft 183, is a crank 184, to which the forward end of a link or lever 185, is connected. The lever 185, is also connected to the depending crank 167. Thus the oscillations imparted to the crank 167, will serve to operate the pivoted shearing blade 182, to cut the paper strip at that point between the upper end of the paper guide and the lower breaker strip 152, of the forming box.

Attached to or formed upon the angle bracket 172, are uprights or bearing blocks 186, in which a pair of connected receiving arms 187, for the ejected wrapped caramels are pivoted. As clearly shown in Fig. 41, a coiled compression spring 188, is mounted beneath said connected arms 187, bearing upwardly therebeneath, and is seated upon the upper surface of the frame casing 169, and acts normally to thrust said arms 187, upwardly into contact with the lower periphery of the wrapping wheel 77. Journaled through an extension on the frame plate 22, is a shaft 189, having secured on its outer end a crank 190, to which a link 191, is connected. The other end of said link 191, is connected to a lever 192, pivoted upon a stud 193, as shown in Fig. 4. Pivoted adjacent to said lever 192, is another lever or crank 194, and said levers are connected to one another at their upper ends by a link 195, which maintains a substantially horizontal position in all its movements for pivotal adjustments of said cranks. The forward end of said link 195, is formed with an ejecting head 196, for the caramels discharged from the wrapping wheel, and said head extends outwardly on each side and slides upon the upper surfaces of said levers 187, between which said links and said cranks 192 and 194, are disposed. Said respective cranks are actuated at the proper instant to eject a wrapped caramel due to a drive imparted to the crank 190, shown in Fig. 27, on the shaft 189. For this purpose, secured on the inner end of the shaft 189, is a gear 197, which meshes with gears 198 and 199, shown in Fig. 12, the latter journaled on the stud on the rear surface of the frame plate 24, and the idler gear 199, meshes with a driving gear 200, which is secured upon the end of the shaft 59, adjacent to the frame plate 24. Mounted within the frame member 169, are the paper feed rollers of the wrapping machine. For this purpose, as shown in Fig. 28, a shaft 201, is journaled in bearings provided in extensions of said frame casing, and secured

thereon are friction rolls 202, four in number, and at the inner end of said shaft is a gear 203. Said gear meshes with another gear 204, secured upon a shaft 205, journaled through the frame plate 22, and at its inner end has secured thereon the gear 198, previously mentioned, and shown in Fig. 12.

As shown in Figs. 29 and 30, lug extensions 206, are formed upon one side of the inner surface of the frame casing 169, and journaled therein is a shaft 207. Secured upon said shaft 207, is a long bracket 208, having journaled therein a tubular member 209, provided at one of its ends with an integral friction roll 210, having secured centrally thereon friction rolls 211. Secured on the forward end of the tubular member 209, is another friction roll 212, provided with an integral knurled adjusting head 213, extending outwardly through an aperture in the cover plate 171. A shaft 214, extends through said tubular member 209, and at its inner end is provided with a gear 215, meshing with the gear 203, and the other end of said shaft is threaded and has secured thereon a locking knurled head 216, beneath which is mounted a washer 217, and a collar 218, threaded upon the end of the tubular member 209, and bearing against the friction roll 212. Secured upon the end of the shaft 207, is a depending crank 219, shown in Figs. 29 and 30, and connected thereto, as shown in Fig. 4, is a link 220, which is in turn connected to a bell crank having one arm 221, and another arm 222, said bell crank being pivoted upon a stud 223, in the front surface of the frame plate 22. A handle 224, is slidably mounted in the end of the crank 222, adapted to engage in either one of two apertures in a bracket 225, secured upon the frame plate 22, to hold said bell crank in either one of two adjusted positions.

As clearly shown in Fig. 29, the respective friction rolls within said casing 169, are cut away for a portion of their periphery so that the extent of rolling contact surface between the opposite rolls may be changed by adjustment of the friction rolls which are mounted upon the tubular member 209. As clearly shown in Figs. 28 and 29, threaded members 226, are engaged through the side wall of the casing 169, and at their inner ends have seated thereagainst coil compression springs 227, which bear against the carrying bracket 208, for the friction rolls, normally thrusting the same against the friction rolls 202.

Pivoted upon a stud shaft 228, secured in an extension of the lower end of the paper tube or guide, are a pair of arms 229, between which is journaled a roller 230, which is normally thrust inwardly against the inner surface of one wall of the paper tube or guide, and beneath which the paper strip

must pass, with a coil spring 231, connected to said arms 229, to normally thrust the roller against the paper. Also secured upon the front surface of the frame plate 22, is a 5 stud shaft on which are journaled a pair of arms 232, with a roller 233, journaled on said stud shaft between said arms and with another roller 234, journaled between said arms at the outer end thereof. Attached 10 upon the inner end of the stud shaft adjacent the frame plate 22, is an adjustable disk 235, and connected thereto and to said arms 232, is a spring 236, which acts normally to swing said arms 232, inwardly toward the stud 228, and the stress upon said 15 spring 236, may be changed by adjustment of the disk 235. A pair of depending arms 237, integral with a bracket piece 238, are secured upon the lower end of the frame 20 plate 22, and rotatably and releasably supported therebetween is a reel of waxed paper 239. Pivoted upon a stud 240, secured also upon the lower end of the frame plate 22, is a bell crank having one arm 241, provided 25 with an adjustable weight 242, and the other arm 243, extending downwardly and pressing inwardly against the paper reel 239, affording a friction brake to prevent spinning of the reel. The strip of paper is led from 30 the reel 239, upwardly around the rollers 234, and downwardly beneath the roller 233, which forms a tension mechanism, and then upwardly beneath the spring impelled roller 230, into the paper tube or guide. The caramels, completely wrapped and ejected from 35 the wrapping wheel onto the receiving arms 187, are thrust therefrom by the ejecting head 196, into a discharge chute 251, supported upon a stud 252, and fitting therein 40 is the strap 112, beneath which the caramels move. The bottom of said discharge chute is a resilient or spring member 253, the end of which bears upwardly beneath the arms 187, and moves therewith, thus adjusting 45 itself for any thickness of caramel.

The operation is as follows:

The operator of the machine stands in the angle inclosed by the discharge chute 251, and the feeding table 1, so that feeding of the 50 caramels as well as packing of the wrapped caramels from the discharge chute may be performed by one person. The caramels are carried by the feed belt toward wrapping position on the wrapping machine, one caramel in each of the pockets formed on the belt, and the stripper blade 16, at the end of the feed table, serves to prevent more than one caramel being carried in a pocket, and serves further to tilt an improperly carried caramel into proper position. The feed belt 9, is driven intermittently from its driving sprocket 42, which in turn is driven by the sprocket wheel 44, with which it is adjustably connected. Said sprocket wheel 44, receives its intermittent drive through a chain 65

and sprocket from the Geneva gear. At the proper interval, the plunger 154, is actuated to thrust the caramel carried into the forming box 137, by the belt 9, through the passage 138, beneath the roller 143, into the receiving pocket in the carrying wheel 77, which at this instant is at rest. Furthermore, a strip of paper has been passed between the breaker strips 151 and 152, and sheared by the shears therebeneath, so that 75 the caramel thrust into the carrying pocket of the wrapping wheel carries the strip of paper therewith which is thereby applied around three sides of the caramel, as shown in Fig. 46. The convergent side walls and 80 top wall of the forming box serve to correct any irregularities in size or shape of the caramels, which, of course, when fresh are somewhat pliable. The relatively light spring impelled friction roll 143, in the top 85 wall of the forming box, prevents the caramel tipping forwardly as it is ejected through the forming box. The top wall of the forming box being formed by the spring impelled pivoted plate 139, permits ready 90 access into said forming box by swinging said plate upwardly against the stress of its spring in the event a caramel should become wedged in the forming box. The feeding plunger 154, is driven forwardly with a sudden and abrupt movement, and is suddenly retracted from the caramel after it has thrust the caramel from the feed belt through the forming box into the wrapping wheel, so that there is but slight tendency 95 for the caramel to stick to the plunger and return therewith. Furthermore, the area of the face of the plunger 154, is considerably less than the area of the discharge opening of the passage 138, of the forming box to 100 obviate collection of caramel material from the walls of the forming box upon the plunger which eventually would cause caramels to stick thereto.

The plunger 154, is driven by the segment 110 gear 157, as shown in Fig. 19, and this in turn is operated by a crank 159, secured upon the same shaft therewith, which is linked to the block 161. The block 161, moves with the bar 162, which is actuated by 115 the link 163, which is connected to the crank 67, attached upon the shaft 66, extending through one side of the front surface of the frame plate 24. This shaft receives its movement from the cam wheel 54, and the 120 rest period and character of movement imparted to said shaft for transmission to the plunger 154, is determined by the shape of the groove 55, in said cam wheel in which the roller travels which is mounted on the 125 crank 68, secured upon the shaft 66.

The operating mechanism which actuates the feeding plunger 154, also actuates the paper shear, but an intermediate timing mechanism is provided to cause operation of 130

- the paper shear just prior to complete movement of the plunger 154, so that the paper strip will be caught between the caramel and the edges of the receiving pocket of the carrying wheel, and prevented from falling from between the breaker strips 151 and 152, when it is sheared from the main strip. This intermediate timing mechanism consists of the cam groove 166, in the block 161.
- 5 10 which serves to actuate the pivoted bell crank, the lower arm 167, of which extends downwardly and is connected to the adjustable link 185. The adjustable link 185, is in turn connected to the crank 184, which is 15 mounted on the same shaft with the pivoted shearing blade or knife 182, thereby actuating the same over the stationary blade or knife 181, between which the paper strip is drawn.
- 20 25 Thus the feeding plunger for ejection of the caramel into the wrapping wheel, as well as the shearing mechanism for cutting the strip of paper for application around the caramel in the wrapping wheel, is actuated primarily from the same cam element, that is, the groove 55, in the cam wheel 54. At the time the wrapping wheel receives the caramel and its strip of wrapping material, the wheel is at rest, and this is the only rest 30 35 interval in the cycle of movement of the wheel, all of the wrapping operations upon the caramel carried thereby being performed and the caramel ejected while the wheel is in motion. The wrapping wheel is secured upon the shaft section 59, which is driven in a counter-clockwise direction, referring to Figs. 14 to 17, inclusive, and receives its drive from the main shaft section 28, which is driven in an opposite direction or clockwise. The counter-clockwise or reverse movement of the wrapping wheel is obtained through the differential or stop motion reversing gear mechanism shown in Figs. 8 and 10. Simply stated, the bevel 40 45 gear 57, secured upon the shaft section 28, drives the bevel gear 64, through the bevel pinions 63, in a reverse direction. When it is necessary, however, to bring the wrapping wheel to rest at the time the caramel carrying pocket is in register with the forming box from which the caramel is received, the spider carrying the small bevel pinions 63, is caused to rotate with the bevel gear 57, thereby rolling the pinions 63, upon the 50 55 bevel gear. The movement causing the shift of the spider carrying the small bevel pinions 63, is imparted thereto by a crank and link connection, which is operated from the cam groove 56, of the cam wheel 54.
- 60 During the time that the carrying wheel is at rest, the spider is being moved at the same rate as the driving gear 57, and after a caramel has been deposited into the pocket in the carrying wheel, the shifting movement of the spider slows down, thus causing the carrying wheel to begin its movement. After the wheel has started movement the spider finally comes to rest in its shifted position, and at this time, of course, the wrapping wheel has increased to normal speed. However, the cam wheel 54, now effects a reverse shift of the spider back to initial position, and this movement causes an acceleration of the carrying wheel, but the carrying wheel again rotates at normal uniform speed after the spider has been shifted to rest in initial position. Thus, there is no shock to the mechanisms in bringing the same to rest, and again setting the same in motion, for the reason that owing to the shape of the cam groove in the cam wheel 54, the bevel pinions on the spider are so shifted that the carrying wheel and other mechanisms are slowly brought to rest, and after the rest period are slowly started again in motion. At the time that the wrapping wheel comes to rest in register with the passage through the caramel forming or feed box, the plunger 92, in the wrapping wheel is in its outer position, but when the caramel is thrust into the wheel pocket between the spring side walls 89, the plunger, which is merely a friction plunger, is thrust inwardly. As the caramel is thrust into the pocket in the carrying wheel, the paper wrapper is applied around three sides of the caramel, as shown in Fig. 46, with the wrapper denoted as a whole by the reference numeral 244.
- When the wrapping wheel begins its movement, as it moves into the position shown in Fig. 14, the folder plate 134, swings inwardly over-traveling the wrapping wheel, and striking one of the upstanding portions of the wrapper to fold the same inwardly over the top side of the caramel, as shown in Fig. 47, and denoted by the reference numeral 245. Immediately thereafter, the wrapping wheel carries the caramel and its wrapper beneath the head 100, of the shoe 99, which bends the other upstanding portion of the wrapper over the top side of the caramel, and as the caramel is carried beneath the stationary shoe 99, folds the same downwardly over the fold 110 115 245, this second fold on the top side of the caramel being denoted by the reference numeral 246. Immediately thereafter, the first end fold is made at each end of the caramel. This is accomplished by the end folder 120 plates 87, one on each side of the wrapping wheel, and movable diametrically with respect thereto, moving from the position shown in Fig. 14, upwardly over the end of the caramel as shown in Fig. 15, and folding the bottom portion of the projecting ends of the wrapper upwardly over the ends of the caramel, as shown in Fig. 48, and de-

noted by the reference numeral 247. This movement of the end folder plates 87, is caused to take place due to the shape of the stationary cam groove 76, in which the roller 5 98, which is mounted on the slideable block of the wrapping wheel, tracks, the end folder plates 87, being attached upon plate members 84, which are secured to said slideable block. As the wrapping wheel continues 10 its movement into the position shown in Fig. 16, the end folder plates 87, are retracted, due to the shape of the cam groove 76, and the end folder arms 121, which have been swung upwardly, as shown in Fig. 15, swing 15 downwardly, as shown in Fig. 16, over-traveling the wrapping wheel to strike the second end fold of the wrapper over the end of the caramel, as shown in Fig. 49, and denoted by the reference numeral 248. The 20 end folder arms 121, move co-incidently with the first side folder 134, that is, as the side folder 134, is swung inwardly, as shown in Fig. 15, the arms 121, swing into their outer extreme position, and conversely, when said 25 arms 121, are swung inwardly to their inner extreme position, as shown in Figs. 16 and 17, the first side folder 134, is swung into its outer extreme position.

The connections between said second end 30 folder members and the first side folder member, as well as the drive therefor, is shown clearly in Fig. 12. The first end folder is mounted upon the shaft 131, and the second side folder member is mounted 35 upon the shaft 120, and said shafts are, as shown, connected through cranks, 125 and 130, by a link 129. Movement is imparted to said connected folder members from the cam wheel 73, provided with the cam groove 40 74, in which a roller tracks which actuates the crank 127, which is connected by the link 126, to the small crank 124, which serves to actuate the shaft 120. Immediately after the second side folder members have folded 45 the portions 248, over the ends of the caramel, the projecting portions of the wrapper, shown in Fig. 49, travel beneath the projecting rounded breaker plates 117, which serve to bend the projecting portions 50 of the wrapper inwardly, and immediately thereafter the wrapping wheel moves into the position shown in Fig. 16, whereby the projecting portions of the wrapper move beneath the spring impelled stationary end folder plates 116, which serve to make the 55 third end fold 249, upon the caramel, as shown in Fig. 50.

During this time, the top side or folded portions 245 and 246, of the wrapper, have 60 been moving beneath the stationary arc-shaped shoe 99, which rests by gravity upon the upper portion of the wrapping wheel, but as the wrapping wheel continues to move, said top side folds are brought beneath 65 the tapered rounded end 101, of the

shoe 99; that is, as the caramel is carried past the end folder plate 116. This movement past the end folder plates 116, has caused the V-tabs 250, formed by the third end fold, to project upwardly or outwardly 70 beyond the periphery of the wrapping wheel, and consequently they strike the projecting V-points 106, shown in Fig. 38, of the stationary shoe 105, and are thereby caused to be folded inwardly over the outer 75 rounded surface of the tapered end 101, of the stationary shoe 99, and finally down upon the top side of the caramel, as shown in Fig. 51. The continued movement of the wrapping wheel with the wrapper folded 80 around the caramel beneath the stationary spring impelled shoe 105, causes the V-points 250, to be creased thereon, thereby locking the entire wrapper upon the caramel.

The travel of the wrapping wheel finally 85 carries the caramel to ejecting position, or that shown in Fig. 17, that is, outwardly from beneath the spring impelled shoe 105. At this time, the shape of the cam groove 76, is such as to cause the end folder plates 87, to again move outwardly and to a greater degree than the movement previously described, so that said plates travel beyond the periphery of the wrapping wheel, and, as a consequence, this extreme 95 movement of the slide block 83, which carries the end plates, causes the plunger 92, of the wrapping wheel, shown in detail in Fig. 5, to be thrust outwardly substantially flush or even a trifle beyond the periphery of the 100 wrapping wheel, thereby ejecting the completely wrapped caramel, the caramel being guided by the end plates 87, which extend beyond the periphery of the wheel. The caramel is thus deposited upon the spring 105 impelled receiving arms 187, thrusting the same downwardly, and, of course, the caramel is moved rearwardly along on said arm until complete ejection, due to the travel of the wrapping wheel. The retractive movement of the caramel upon said arms 187, is stopped by the ejecting head 196. As the wrapping wheel, after ejection of the caramel, continues its movement, the shape of the cam groove 76, causes the end folder plates 110 87, to be drawn inwardly into the retracted position shown in Fig. 14, but, of course, the plunger remains in its outer position until again forced inwardly due to another caramel being thrust into the wrapping 115 wheel pocket, when the same comes to rest before the forming box 137. The ejector head 196, is then positively actuated to thrust the caramel outwardly along the arms 120 187, into the discharge chute 251.

This mechanism is caused to operate by the rotation of the crank 190, which is connected by its shaft to the gear 197, and rotation of said crank imparts a reciprocating movement through the link 191, to the for- 125 130

ward discharge or ejecting arm 192, which is pivotally connected by the ejector bar 195, to the other ejecting arm 194. Of course, the gear connection which operates the 5 crank 190, from the shaft section 59, as shown in Fig. 12, is so timed that a forward or ejecting movement of said arms by which the ejector head 196, is thrust forward, takes place after the caramel pocket in the wrapping wheel has passed ejecting position, and after an ejection of a caramel has been made by said mechanism, the same is returned to retracted or initial position, ready to receive another caramel ejected from the 10 wrapping wheel.

The paper for the machine is fed from the reel 239, contacted by the weighted friction arm 243, which acts as a brake to prevent overrunning of the reel, and the paper 15 is led upwardly around the roller 234, and downwardly beneath the roller 233, between the arms 232, which are spring impelled and thus afford a tension mechanism, and then upwardly into the paper guide or tube beneath the spring impelled roller 230. The paper is drawn upwardly through the tube from the roller 230, by paper feeding means, which, as shown in Figs. 27 and 31, inclusive, 20 embraces segmental friction rollers 202 and 210, 211 and 212. The central rolls engage through slots provided therefor in the paper tube. The rolls 210, 211 and 212, are adjustable whereby different lengths of the 25 segmental periphery of said rolls may be caused to contact to feed different lengths of paper upwardly through the tube for each 30 intermittent driving movement imparted to the feed mechanism.

Adjustment of said friction rolls 210, 211 35 and 212, to vary the length of paper fed by the feeding mechanism is effected by loosening the knurled head 216, and then turning the knurled head 218, which is secured upon the tubular member 209, there- 40 by adjusting all of said rolls 210, 211 and 212, through the desired angle to effect any desired length of contact with the respective segment rolls 202. If, at any time, it is desired to throw the paper feeding means out 45 of operation, the lever 222, shown in Fig. 4, is swung upwardly by its handle 224, and locked in the latch plate 225, thereby, through the link connection 220, moving the crank 219, to the left, and swinging the 50 rolls 210, 211 and 212, out of contact with the rolls 202, about the pivot shaft 207, shown in Fig. 29. The spring impelled roll 230, then serves to prevent the paper strip 55 from sliding downwardly through the paper tube.

The drive for the wrapping wheel, the folder devices, the paper feeding means and the ejecting mechanism is all received 60 through the stop or differential gear mechanism 57, 63—64; whereas the caramel feeding

mechanism and shearing means are operated from the main shaft 28. As a result, when the stop mechanism operates, all of the means in train therewith come to rest, and this is desirable as it is only necessary at 70 this time to feed a caramel and its wrapper into the wrapping wheel.

I am aware that various details of construction may be varied through a wide range without departing from the principles 75 of this invention, and I therefore do not purpose limiting the patent granted otherwise than necessitated by the prior art.

I claim as my invention:

1. In a wrapping machine of the class de- 80 scribed, a carrying wheel for the articles to be wrapped, folder devices operating to completely fold a wrapper on the article during its movement with said wheel without cessation in movement of the wheel, and means within said wheel movable by certain of said folder devices to eject the wrapped article from said wheel.

2. In a wrapping machine of the class de- 90 scribed, a wrapping wheel adapted to receive an article, folder devices for applying a wrapper on said article, and a shiftable reverse gear differential mechanism, by its shifting movement intermittently driving said wheel and folder devices. 95

3. In a wrapping machine of the class de- 100 scribed, a wrapping wheel adapted to receive an article with a wrapper to carry the article in fixed relation with respect to said wheel, folder devices operating to fold the 105 wrapper around the article during movement of the wheel without cessation in movement of the wheel, and other folder devices overlapping one another and bearing on the periphery of the wheel to receive portions of the wrapper therebetween and the article therebelow to complete the wrapping of the article.

4. In a wrapping machine of the class de- 110 scribed, a wrapping wheel adapted to carry 115 an article with a wrapper thereon, folder devices operating to completely fold the wrapper on the article during movement of the article with said wheel, and ejecting means having a lost motion connection with certain of said folder devices adapted to eject the wrapped article from the wrapping wheel.

5. In a wrapping machine of the class de- 120 scribed, a wrapping wheel adapted to carry an article, folder devices operating to completely fold the wrapper on the article carried in the wheel, and mechanisms having a lost motion connection with certain 125 of said folder devices, for ejecting the article from the wheel after completion of the wrapping, certain of said folder devices adapted to move with the article during ejec- tion thereof to guide the same.

6. In a wrapping machine of the class 130

described, a wrapping wheel, having a pocket therein, to receive an article and wrapper thrust thereinto whereby the wrapper is applied around three sides of the article, a folder device exterior of, and overtraveling the moving wrapping wheel to fold one portion of the wrapper on the top side of the article, another stationary folder device operating to fold another portion of the wrapper in overlapping relation thereon on the top side of the article, as the wheel continues its movement, end folder plates carried on the wrapping wheel and slidably movable diametrically thereacross to make end folds of the wrapper on the article, and folder devices exterior of the wheel operating to complete the end folds on the wrapper as the movement of the wrapping wheel continues, and stationary mechanism to fold the projecting end portions of the wrapper downwardly on the top side thereof to complete the wrapping operation as the wheel continues its movement with the article.

7. In a wrapping machine of the class described, a wrapping wheel having a pocket therein for an article, top side folder devices adapted to fold a wrapper in overlapping relation on the top side of the article, an end folder device associated with the wheel to make the first end fold at each end of the wrapper on the article, swinging folder arms adapted to make second end folds of the wrapper on the article as the wheel continues its movement, stationary end folder plates to make third end folds of the wrapper on the article, and stationary interfitting means peripheral of the wheel adapted to receive the wrapper therebetween to complete the folding operation of the wrapper on the article.

8. In a wrapping machine of the class described, a rotating article carrying means, folder devices mounted exterior thereof to fold a wrapper on an article carried in said means, cam actuated folder mechanism associated with said means and rotatable therewith and slidably diametrically thereacross to assist in the folding operation, and means mounted in said article carrying means and having a lost motion connection with said folder mechanism to eject the article after completion of the wrapping.

9. A wrapping machine of the class described comprising a rotatable article carrying wheel, folder devices adapted to apply a wrapper upon the article carried by the wheel, and ejecting means mounted within the wheel and operated by certain of said folder devices for ejecting the article from the wheel after completion of the wrapping of the article.

10. A wrapping machine of the class described comprising an article carrying wheel, folder devices operating to completely wrap the article while carried in said

wheel without stoppage of the wheel, and means adapted to be operated by one of said folder devices to cause ejection of the wrapped article from the wheel.

11. In a wrapping machine of the class described, a drive shaft, a bevel gear thereon, a shaft section alined with said drive shaft, another bevel gear thereon, a spider between said bevel gears, bevel pinions journaled on said spider affording a driving connection between said bevel gears, a wrapping wheel mounted on the outer end of the second shaft section, folder devices driven from said second shaft section and associated with said wrapping wheel, and cam operated means operated from said first shaft section to cause shifting of said bevel pinion spider to cause a stop movement of said second shaft section and all parts driven therefrom.

12. In a wrapping machine of the class described, a main drive, a wrapping wheel, a stop movement drive therefor driven from said main drive, folder devices associated with said wrapping wheel, certain thereof stationary and others movable, said movable folder devices operated through the stop movement drive for the wrapping wheel, a paper feed mechanism operated through the stop movement drive for the wrapping wheel and brought to rest when said wrapping wheel stops movement, and caramel feeding and paper shearing means operated from the main drive of the machine and operating when said wrapping wheel and other mechanisms are at stop position.

13. In a wrapping machine of the class described a wrapping wheel, folder devices mounted thereon and movable therewith operating to fold a wrapper on an article carried by said wheel, and ejecting mechanism associated with said wheel, said ejecting mechanism operated by one of the folder devices to eject the completely wrapped article from the wheel.

14. In a wrapping machine of the class described, a main drive shaft, a shaft driven thereby, a reverse gear differential mechanism, shiftable to cause an intermittent drive to said driven shaft from said drive shaft, a wrapping wheel driven by said driven shaft, folder devices and paper feed mechanisms driven by said driven shaft, and shifting means for said reverse mechanism operated from said drive shaft to effect an intermittent drive to said driven shaft.

15. A wrapping machine of the class described comprising means to receive an article placed therein with the wrapper disposed around three sides of the article, mechanism folding one margin of the wrapper over the fourth side of the article, mechanism folding the opposite wrapper margin in overlapping relation over said first fold on the article, mechanism operat-

ing thereafter to effect an end fold of the wrapper at each end of the article, means operating in sequence to effect two more end folds of the wrapper at each end of the article, means folding the remaining portions of the wrapper over the fourth side of the article over the overlapping side folds thereof, and means operated by said first end folding mechanism for ejecting the wrapped article.

16. In a machine of the class described, an intermittently driven article feed mechanism, an intermittently driven wrapping wheel adapted to receive an article deposited therein together with a strip of wrapping material, folder devices operating to completely fold the wrapping strip around the article while it is carried on the wrapping wheel without stopping of the wrapping wheel, and means adapted to be operated by one of said folder devices to eject the wrapped article from the wheel.

17. In a wrapping machine of the class described, a rotatable article carrying member, means for carrying an article therewith, mechanism rotatable with said member to fold a wrapper upon the article, means adjustably mounted and held in stationary position bearing upon said rotatable member to fold the wrapper upon the article carried by said member, and radial ejecting means in said member connected with and operable by said folder mechanism to cause ejection of the wrapped article.

35 18. In a wrapping machine of the class described, a drive shaft, a driven shaft, a reverse gear differential mechanism between said shafts whereby the driven shaft is driven reversely to and by said drive shaft, mechanisms shiftable by said drive shaft to shift said reverse gear mechanism to bring said driven shaft to rest for an interval of time, a rotatable wrapping member driven by said driven shaft, a plurality of folder devices associated therewith, certain thereof operated by said driven shaft, an article feeding mechanism operated by said drive shaft, and a paper feed mechanism operated by said driven shaft.

50 19. In a wrapping machine of the class described, an intermittent feed mechanism for the articles, an intermittent paper feed device, shearing mechanism to shear the paper to provide a wrapper for each article, a wrapping member to receive the article and its wrapper therein when in a rest position, and a reverse gear differential mechanism for driving said member to continuously move the article while said wrapper is folded around the article, said mechanism comprising in part gears shiftable forwardly and reversely to change the character of movement of said wrapping member.

65 20. In a wrapping machine of the class described, a rotatable carrying member for

the articles to be wrapped, folder devices operating to completely fold a wrapper on the article during its movement with said wheel without cessation in movement of the wheel, and ejecting means operated by certain of said folder devices to eject the wrapped article from said member.

21. In a wrapping machine of the class described, a rotatable wrapping member adapted to receive an article to apply a wrapper thereon and to carry the article in fixed position until completion of the wrapping, folder devices operating to fold the wrapper around the article while carried without cessation in movement of said member, and a cam controlled stop motion mechanism driving said member and said folder devices.

22. In a wrapping machine of the class described, a wrapping wheel adapted to receive an article together with a wrapper to carry the article in fixed relation with respect to said wheel, stationary and movable folder devices operating to fold the wrapper around the article during movement of the wheel without cessation in movement of the wheel, and ejecting means connected with and movable by certain of said movable folder devices adapted to eject the completely wrapped article from the wheel.

23. In a wrapping machine of the class described, a wrapping member adapted to receive an article thrust horizontally therein together with a wrapper, folder devices operating to completely fold the wrapper on the article during movement of the article, and ejecting means mounted radially in said member and operating to eject the completely wrapped article vertically from, and during movement of said member.

24. In a wrapping machine of the class described, a wrapping wheel adapted to carry an article, stationary and power driven movable folder devices operating to completely fold the wrapper on the article while carried in the wheel, and mechanisms operated by certain of said movable feeder devices for ejecting the article from the wheel after completion of the wrapping.

25. In a wrapping machine of the class described, a wrapping wheel having a pocket therein to receive an article and wrapper thrust thereto whereby the wrapper is applied around three sides of the article, a folder device over-traveling the moving wrapping wheel to fold one portion of the wrapper on the top side of the article, another folder device operating to fold another portion of the wrapper in overlapping relation thereon on the top side of the article as the wheel continues its movement, end folder plates to make the first end folds of the wrapper on the article, end folder devices operating to complete the end folds on the wrapper as the movement of the wrap-

- ping wheel continues, mechanism to fold the projecting end portions of the wrapper downwardly on the top side thereof over said overlapping first side folds to complete 5 the wrapping operation as the wheel continues its movement with the article carried therein, and means adapted to be operated by said first end folder plates to eject the wrapped article from the wheel.
- 10 26. In a wrapping machine of the class described, a wrapping wheel having a pocket therein to receive an article thrust horizontally therein, side folder devices adapted to fold a wrapper in overlapping 15 relation on the top side of the article, end folder devices associated with the wheel to make the first end fold at each end of the wrapper on the article, swinging folder arms adapted to make second end folds of 20 the wrapper over the first end folds on the article as the wheel continues its movement, stationary end folder plates to make third end folds over the first and second end folds of the wrapper on the article, stationary 25 means operating to fold the end portions of the wrapper on the side of the article over said first overlapping side folds of the wrapper, means ejecting the article vertically from the wheel.
- 30 27. In a wrapping machine of the class described, an intermittently driven wrapping wheel having a pocket to receive an article thrust horizontally therein to be wrapped, means to completely fold the 35 wrapper on the article during movement of the article with the wheel, ejecting mechanism associated with the wheel to eject the wrapped article vertically from the moving wheel, and certain of said folder means moving 40 with the article during ejection thereof to guide the ejected article.
28. In a wrapping machine of the class described, an article carrying wheel adapted to receive an article and a wrapper with the 45 wrapper applied around three sides of the article, stationary and movable wrapper folder devices exterior of the wheel for folding the wrapper on the article, as the wheel moves, folder means associated with the 50 wheel rotating therewith and moving relative to the wheel to assist in folding the wrapper upon the article, and means independent of the folder means for ejecting the article from the wheel, said folder means 55 moving with the article during ejection from said wheel to guide the article.
29. In a wrapping machine of the class described, a rotating article carrying means, stationary and movable folder devices 60 mounted exterior thereof to fold a wrapper on an article carried in said means, folder mechanism associated with said means, rotatable therewith and slidable relative thereto to assist in the folding operation, and means mounted in said article carrying means capable of movement independently of said folder mechanism to eject the article after completion of the wrapping, said folder mechanism moving into position to guide the article during ejection thereof. 65
30. In a wrapping machine of the class described, a rotatable carrying wheel, slidable folder mechanism associated therewith, a stationary cam mechanism adapted to cause operation of the folder device on said 70 wheel as the wheel rotates, power driven folder devices mounted exterior of and adjacent to said wheel to fold a wrapper on an article carried by said wheel, and ejecting means associated with said wheel operated by said folder mechanism to eject the article from the wheel. 75
31. A wrapping machine of the class described comprising a rotatable article carrying wheel, folder devices adapted to overtravel the wheel in its movement to apply a wrapper upon the article carried by the wheel, ejecting means mounted within the wheel for ejecting the article therefrom after completion of the wrapping of the article, and other folder devices mounted on the wheel adapted to operate said ejecting means. 80
32. A wrapping machine of the class described comprising an article carrying wheel, folder devices operating to completely wrap the article while carried in said wheel without stoppage of the wheel, and an ejecting means operated by one of said folder devices with said folder device moving into position to guide the article when ejected. 85
33. In a wrapping machine of the class described, the combination with a drive shaft, of a gear thereon, another shaft to be 90 driven by said drive shaft, a gear on said driven shaft, a spider between said gears, pinions journaled on said spider affording a driving connection between said gears, a wrapping wheel and folder devices driven by said second shaft, and cam operated means operated from said first shaft to cause shift of said pinion spider to cause a stop movement of said second shaft. 95
34. In a wrapping machine of the class described, a drive shaft, a gear thereon, another shaft to be driven by said drive shaft, a gear on said drive shaft, a spider between said gears, pinions journaled on said spider affording a driving connection between said 100 gears, a wrapping wheel mounted on the outer end of the second shaft section, folder devices driven from said second shaft section and associated with said wrapping wheel, and cam operated means operated from said first shaft to cause shift of said pinion spider to cause a stop movement of said second shaft. 110
- 60 115
- 120
- 125

35. In a wrapping machine of the class described, a main drive, a wrapping wheel, a stop movement drive therefor driven from said main drive, folder devices associated with said wrapping wheel, certain thereof stationary and others movable, a paper feed mechanism operated from the stop movement drive, and caramel feeding and paper shearing means operated from the main drive of the machine. 70
36. In a wrapping machine of the class described, a carrying member, driving means therefor, folder devices mounted on said member and movable therewith operating to fold a wrapper on an article carried by said member, and ejecting mechanism associated with said member, said ejecting mechanism operated by the folder devices to eject the completely wrapped article from said member, and said folder devices moving with the article to guide the same during ejection. 80
37. In a wrapping machine of the class described, a main drive shaft, a shaft driven thereby, a reverse gear stop mechanism shiftable to cause an intermittent drive to said driven shaft from said drive shaft, a wrapping wheel driven by said driven shaft, folder devices and paper feed mechanisms driven by said driven shaft, shiftable means forming a part of said reverse gear stop mechanism, and a cam on said drive shaft to shift said means to effect an intermittent drive to said driven shaft. 90
38. A wrapping machine of the class described comprising revolving means to receive an article placed horizontally therein with the wrapper disposed around three sides of the article, mechanism folding one margin of the wrapper over the fourth side of the article, mechanism folding the opposite wrapper margin in overlapping relation over said first fold on the article, diametrically slidable mechanism on said revolving means operating thereafter to effect an end fold of the wrapper at each end of the article, means operating in sequence to effect two more end folds of the wrapper at each end of the article, means folding the remaining portions of the wrapper over the fourth side of the article over the overlapping side folds thereof, and mechanism mounted on said revolving means to eject the article downwardly therefrom. 100
39. In a machine of the class described, an intermittently driven article feed mechanism, an intermittently driven wrapping wheel adapted to receive an article deposited therein together with a strip of wrapping material, folder devices operating to completely fold the wrapping strip around the article while it is carried on the wrapping wheel without stopping of the wrapping wheel, and ejecting means operated by certain of said folder devices for ejecting the completely wrapped article. 115
40. In a wrapping machine of the class described, a wrapping wheel, stationary and movable folders thereon, a stop motion for said wheel and folders comprising a differential gear mechanism, a cam wheel, and a spider pivotally mounted carrying parts of said differential gear mechanism and operated by said cam wheel whereby the wrapping wheel and folders are brought slowly to rest, held at rest, and started slowly in motion again. 125
41. In a machine of the class described, a wrapping wheel, folding mechanisms thereon, driving means for said wrapping wheel and folding mechanisms, a stop mechanism forming a part thereof whereby said wrapping wheel is brought slowly to rest, and after a rest period started slowly in motion. 130
42. In a machine of the class described, a wrapping mechanism, folding means thereon, a stop motion drive for said mechanism and means embracing a pair of bevel gears, pinions interposed therebetween to transmit a drive from one gear to the other, a spider on which said pinions are mounted, and means operated by the driving mechanism to shift said spider and pinions to bring said wrapping mechanism slowly to rest, and after a rest period start the same slowly in motion, without change in speed of the driving bevel gear. 135
43. In a machine of the class described, a wrapping mechanism, folder devices forming a part thereof, a stop motion drive for said wrapping mechanism and folder devices comprising driving and driven bevel gears, bevel pinions interposed therebetween, and mechanism for effecting a shift of said bevel pinions relative said bevel gears to vary the rate of drive therebetween during a shifting movement and to cause a cessation in movement of the wrapping mechanism and folder devices. 140
44. In a machine of the class described, a carrying wheel adapted to receive an article and sheet of wrapping material deposited therein for movement therewith, folder devices to effect side and end folds of the wrapper around the article, certain of said folder devices interfitting and spaced from one another and resting on the periphery of said carrying wheel to receive the article therebeneath with parts of the wrapper positioned to pass between said interfitting folder devices to complete the wrapping of the article. 145
45. In a wrapping machine of the class described, a wrapping wheel having a pocket therein for an article, side folder devices adapted to fold a wrapper in overlapping relation on the top side of the article, end folder devices associated with the wheel to make the first end fold at the end of the wrapper on the article, swinging folder arms adapted to make second end folds of the article. 150

- the wrapper over the first end folds on an article as the wheel continues its movement, stationary end folder plates to make third end folds over the first and second end folds 5 of the wrapper on the article, and stationary means operating to fold the end portions of the wrapper on the side of the article over said first overlapping side folds of the wrapper.
- 10 46. In a machine of the class described, means to receive an article for wrapping, folder devices and ejecting mechanism having a lost motion connection therewith, the folder devices operating to assist in applying the wrapper upon the article and the ejecting mechanism discharging the article after completion of the wrapping.
- 15 47. In a wrapping machine of the class described the combination with folding devices of an ejecting mechanism, said ejecting mechanism operated by the folder devices to eject a wrapped article from the machine.
- 20 48. In a wrapping machine of the class described, a carrying element for the article 25 to be wrapped, ejecting means associated with the element, folder devices mounted on the element, a lost motion connection between said folder devices and said ejecting means for operation of one by the other, and 30 means receiving an article horizontally into said element, said ejecting means ejecting the wrapped article vertically from said element.
- 25 49. In a wrapping machine of the class described, a carrying element for an article 35 to be wrapped, swingingly mounted mechanism exterior of the element adapted to overtravel the element in the direction of movement thereof to assist in folding a 40 wrapper on the article, pivotally mounted means one on each side of the element to overtravel the same and assist in folding the wrapper upon the article, and a connection between said means and mechanism whereby 45 one swings forwardly for a folding operation as the other is retracted and vice-versa.
- 30 50. In a wrapping machine of the class described, a carrying element for the articles to be wrapped, folder devices operating to 50 completely fold a wrapper on an article during its movement with said element, certain of said devices mounted exterior of the element and pivoted to move relatively thereto and interconnected for synchronous operation 55 with respect to the movement of said element.
- 35 51. In a wrapping machine of the class described, a carrying element for the articles to be wrapped, folding devices to completely 60 fold a wrapper on an article during its movement with said element, certain of said folding devices mounted on said element and movable relatively thereto, other folding devices mounted exterior of said 65 element and interconnected with one another for synchronous operation with respect to the movement of said element, and means positively ejecting the wrapped article from the element.
- 40 52. In a wrapping machine of the class described, a wrapping element adapted to receive an article to apply a wrapping thereon, folder devices operating to fold the wrapper around said article while carried in said element, certain of said devices 70 mounted on said element and movable relatively thereto, other of said devices pivotally mounted exterior of said element and interconnected with one another and operating in sequence to impart a series of folds 75 to the wrapper, and means for ejecting the wrapped article from said element, said means operable by one of the folder devices.
- 45 53. In a wrapping machine of the class described, a carrying element for an article to be wrapped, folder devices operating to completely fold a wrapper on an article during its movement with said element, certain of said folder devices movably mounted exterior of said element and interconnected with one another for synchronous operation with respect to the movement of said element and other of said folder devices movably mounted to project beyond 90 the carrier element and afford a guide for the wrapped article when discharged.
- 50 54. A wrapping machine comprising a wrapping element to carry an article, folder devices to fold a wrapper around said article 100 while in said element, receiving means to receive the wrapped article ejected from said element and said receiving means holding the article thrust against the periphery of said element after discharge therefrom.
- 55 55. In a wrapping machine, rotative carrying means for an article, stationary devices operating to fold a wrapper on the article as the article is carried by said means, radially movable mechanisms mounted on 110 said rotative means and movable around therewith to impart a fold to the wrapper, and a receiving means for the wrapped article adapted to be moved by ejection of an article thereto from said carrying means 115 and to be held in its moved position by the article bearing against said carrying means.
- 60 56. In a wrapping machine a rotative carrying member having a pocket in its periphery to receive an article, a forming box with which said pocket is adapted to be brought into register, article feeding means movable through the forming box, and shifting mechanism for thrusting an article from said means through the forming box and into the pocket in the carrying member.
- 65 57. In a wrapping machine a rotative carrying member having a pocket in its periphery to receive an article and its 120

wrapper, a forming box with which said pocket is adapted to be brought into register, article feeding means movable through the forming box, feeding devices to feed a sheet of wrapping material in front of said forming box and ejecting mechanism to thrust the article from said feeding means through said forming box and with the wrapping sheet into said pocket in the carrying member.

58. In a candy wrapping machine, a rotary candy carrying element, means for making the first fold, a gravity acting ele-

ment coöperating with said rotary element for making the second fold, and means for 15 making the remaining folds while the candy is acted upon by said gravity acting element.

In testimony whereof I have hereunto subscribed my name in the presence of two 20 subscribing witnesses.
